EMILE ROSENWALD, OF PARIS, FRANCE.

BUTTON-MAKING MACHINE.

SPECIFICATION forming part of Letters Patent No. 761,544, dated May 31, 1904.

Application filed October 29, 1902. Serial No. 129,246. (No model.)

To all whom it may concern:

Be it known that I, EMILE ROSENWALD, mechanical builder, of 5 Rue du Ponceau, in the city of Paris, Republic of France, have invented a Button-Making Machine, of which the following is a full, clear, and exact description.

This invention relates to the manufacture by mechanical means of buttons made of vegetable ivory (corozo) or other materials capable of being worked in a similar manner.

The new method of manufacture consists in subjecting the pieces or blanks of corozo or other material to the successive action of various tools coacting to form the button in such manner that at every step made by the table of the machine the various operations required for the manufacture of the button will be simultaneously performed, the result being that at each step made by the table a finished button will be delivered from the machine, while there will always be a number of buttons simultaneously in course of manufacture corresponding to the number of stages of the operation. According to this system the blanks of corozo from which the buttons are to be formed are placed in clips upon the machine-table, to which intermittent rotary motion is imparted, whereby each of the blanks is first brought beneath drilling-tools for forming any required number of holes in the button. In the machine represented in the accompanying drawings there are two drills for piercing buttons with two holes.

After having been drilled each blank is brought beneath a profiling or shaping tool and then over a finishing and separating tool, which completes and detaches the button. At each step of the machine there will be two buttons being drilled, one being profiled and one being separated, all the tools operating simultaneously and a finished button being delivered at each movement of the table.

The accompanying drawings illustrate an example of the machine comprising the combination of mechanism employed for the manufacture of buttons in the manner specified.

Figure 1 is a vertical section on line A B of Fig. 3. Fig. 2 is a part sectional eleva-

tion of the machine looking toward the finishing-tool, and Fig. 3 is a plan of the machine complete. Fig. 4 is a detail view of the drills. Fig. 5 shows the lower end of the receiver for the finished buttons. Figs. 6, 7, 8, and 9 show details in side and face views of the mechanism for holding the table in the various positions corresponding to the different stages of operation of the tools. Figs. 10 and 11 show diagrammatic views of the different stages of manufacture of the buttons by means of the machine shown on the drawings.

The same letters of reference denote like parts in the several figures.

The essential part of the machine is formed by the table or ring *a*, receiving intermittent rotary motion and provided with spring-clips *b* for clamping the blanks to be brought successively under the action of the several tools employed in making the button. In order to prevent the clips *b* from shifting during the action of the tools, they are clamped by means of a hinged part *b'*, which is turned down when it is necessary to open the clips.

When it is desired that each tool should produce one button only from each blank, the intermittent movement of the table would be regular, and this would be more generally the case, although the machine shown is designed to produce two buttons from the same blank, in which case each angular movement of table *a* for bringing the different blanks beneath each tool will be made up of two movements—viz., a movement bringing beneath the tool the part of the blank from which the one button is to be produced and a movement of smaller amplitude for presenting to the tool that portion of the blank from which the second button is to be produced. Each tool thus performs two consecutive operations upon each blank at points corresponding to the distance from center to center of the two buttons to be made from the same blank. The sum of these two movements is equal to the pitch of the clips.

The intermittent motion of table *a* is imparted by the following arrangement: The table *a* carries an internal toothed ring *a'*,

- with which meshes a pinion c , keyed on the same shaft as pulley c' , which receives motion by means of a band d from a pulley e , keyed on the shaft of a worm-wheel e' , gearing with 5 a worm f upon a main driving-shaft f' . The intermittent rotary motion imparted to the table a is regulated by the following mechanism: The table a is provided upon its under side with a ring a^2 , provided with escapement-notches $a^3 a^4$, each preceded by an escapement-tooth $a^5 a^6$, the pitch of the notches, and consequently of the teeth, being alternately long and short (see Figs. 2, 7, 9) to correspond to the two movements which the table a is to receive. Beneath the ring a^2 is mounted an escapement-detent g , pivoted upon an axis g' , carried by the upper portion of a lever g^2 , pivoted upon a center g^3 , said lever being held in the position shown in Fig. 6, so as 15 to present the detent g in the path of tooth a^5 by the action of one arm of an elbow-lever h , turning about a center h' , Fig. 1, whose other arm is jointed to a connecting-rod h^2 , connected to the pin of a crank-disk h^3 , keyed on the 20 shaft of a worm-wheel h^4 , gearing with the worm f on main shaft f' . When one of the teeth a strikes against the detent g , the latter, whose angular movement is limited, arrests the ring a^2 , and therefore 25 table a , and the belt d then slips upon the pulley c' . The detent g arrests the ring a^2 , as in Figs. 6 and 7, in position to present the notch a^3 , following the said tooth a^5 , in line with a locking-detent g^4 , carried by lever g^2 . The 30 lever h on being drawn in the direction of the arrow, Fig. 8, by the crank h^3 permits detent-lever g^2 under the action of its spring to engage its detent g^4 in the notch a^3 , Figs. 8 and 35 9. The ring a^2 is thus held stationary during 40 the whole time required for the tool to operate upon the part of the blank presented to it and which corresponds to the first button. By this forward movement of the lever g^2 the detent g escapes from the tooth a^5 and is 45 brought by its spring into the position shown in Fig. 9, so as to be out of the path of tooth a^5 , when by the backward movement of lever g^2 the detent g is again brought into the path of the ring a^2 . 50 When the tools have completed their work, the lever h again acts on lever g^2 , so as to disengage the detent g^4 from notch a^3 , whereupon the belt drives the pulley c' and table a receives its second angular movement limited 55 by the engagement of detent g with the next following tooth a^6 , in which position the next notch a^4 registers with the detent g^4 , which enters it as before, so as to again hold the table stationary during the operation of the 60 tools upon the portion of the blank corresponding to the second button. When the operation is completed, detent g^4 is withdrawn from notch a^4 , and the table then receives such an amount of angular movement as to ad-

vance each blank to the next following tool, 65 said movement being limited by the next following tooth a^6 meeting the detent g , as before described.

The blanks are first drilled. In the machine illustrated there are two drills $i j$, Fig. 4, so mounted as to drill simultaneously on each of two different blanks one of the two holes which each button should have. 70

The drills should be lowered into work and raised immediately afterward to allow the feed movement of the table. To this end the two drill-spindles are engaged by a cross-head k on a lever-arm pivoted upon a shaft k' , having a lever k^2 connected by a link k^3 with the pin of a crank-disk k^4 , fast on the shaft 80 of a worm-wheel k^5 , driven by worm f on the main shaft f' . In order to avoid breakage by excessive resistance to the descent of the drills, the lever k^2 is made in two parts hinged together at k^6 and connected by a spring k^7 , 85 as shown in Fig. 1.

Rotary motion is imparted to the drills by belt-pulleys $i' j'$, which while driving the drill-spindles allow of their vertical movement, the pulleys $i' j'$ being driven by a belt 90 J from a pulley f^2 , fast on the main shaft f' .

The blank after being drilled is brought beneath the profiling or shaping tool m while fresh blanks are brought under the drills. The profiling-tool is also adapted to be brought 95 down into work and to be raised again after performing its function, for which purpose its spindle is engaged by the forked arm m' of a lever pivoted at m^2 and whose other arm, m^3 , is spring-jointed and coupled by a link m^4 100 to the pin of a crank-disk m^5 , fast on the shaft of a worm-wheel m^6 in gear with worm f . The tool is driven from a pulley f^3 by a belt n on pulley n , which allows the vertical movement of the tool-spindle. Upon the tool-spindle are also mounted blades m^7 , which by 105 their rapid rotation disperse the dust produced in the operation.

The profiling-tool shapes the outline or profile of the button in the different blanks as they are presented to it. The blanks having been thus drilled and profiled are then presented to a final separating-tool o , by which the button is finished and detached. This tool, which is placed below the table a , as 110 shown in Fig. 1, consists of a kind of punch having the profile which the button is to receive upon the opposite face to that produced by the preceding profiling-tool, said tool also having both a vertical and rotary movement. 115 The vertical movement is regulated in such manner that the tool is brought into and out of work at the proper moments by a fork o' , fast on the axis h' of the elbow-lever, which controls the intermittent rotary motion of 120 table a .

Rotary motion is imparted to the tool by means of a pulley o^2 , allowing of the vertical

movement of the tool-spindle and driven by a belt o^3 from a pulley f^4 , fast on the main shaft f^1 .

Above the table in line with the tool o is mounted a receiving-tube p , Fig. 5, provided at its lower end with grippers p' , said tube being lowered down onto the blank when the tool is raised into work, so as to grip the separated button. The buttons are successively forced up the tube p and out at the upper end to the tube into a receptacle closed, as by a wire-gauze cap p^2 , to prevent them from flying out.

The vertical movement of the receiving-tube p is produced in the following manner: The tube is carried by an arm p^3 , mounted upon a shaft p^4 , upon the end of which is an arm p^5 . At the moment when it is required to raise tube p to permit of table a being rotated for presenting another button to the action of the stamping-tool the end of arm p^5 is forced backward by a toe p^6 on a tripper-rod p^7 , actuated by a crank-disk p^8 , fast on the shaft of crank-disk b^3 , the free end of the rod p^7 being supported by a friction-roller q .

When the rod p^7 is at a certain inclination, the toe p^6 escapes from the arm p^5 , whereupon a spring p^9 produces the sudden descent of the receiving-tube, and the rod p^7 , passing below the horizontal in its backward movement, brings back the toe p^6 into position to again act on arm p^5 at the next forward movement of the tripper p^7 .

The driving-shaft may have a stopping and starting clutch r , controlled by a lever r' , and the main shaft may be driven by a belt, as shown, from any suitable source of power. It should be understood that during every stoppage of the table a the several tools all act simultaneously, so that there will be always four blanks undergoing different stages of manufacture at the same time, as shown in Fig. 10, viz: first, drilling the left-hand hole; second, drilling the right-hand hole; third, profiling; fourth, separation and expulsion of the button. Fig. 10 shows these four operations as being performed simultaneously upon four blanks brought opposite the different tools and presenting to the latter the part of each blank which corresponds to the left-hand button. Fig. 11 shows these same four operations being performed upon the same blanks after they have been shifted in position beneath the tools for the purpose of bringing under the action of the tools the parts corresponding to the right-hand buttons. The attendant has only to place a blank in each of the clips in turn, while a finished button is delivered at each movement of the table from the moment when the first button has undergone an entire set of operations. The same blank may be passed several times through the machine so long as sufficient material remains for making a button. In this case the

attendant merely shifts the blank in the clip, ⁶⁵ so as to present a fresh portion of the material to the action of the tools.

The buttons may be drilled with any number of holes, the drills being arranged accordingly, and the machine may be adapted for ⁷⁰ making other articles, requiring to undergo similar operations, besides buttons.

The number of tools employed in combination with the table or ring may be varied according to the number of passes or phases ⁷⁵ needed for making the button or other article, as well as the kind of tools, according to the nature of the article to be produced.

The forms, dimensions, details, and materials employed in the construction of the machine ⁸⁰ may also be varied without in any way changing the nature of the invention.

I claim—

1. A machine for forming two buttons from a single blank, said machine comprising a circular table provided with clips for holding the blanks and receiving intermittent rotary motion of angular extents adapted to cause the several blanks to be presented to the different tools determined by an escapement mechanism arranged to operate in such manner that the movements are ultimately long and short, the one movement having for effect to bring opposite each tool the part of the blank corresponding to the one button, and the other ⁹⁰ movement the part of the blank corresponding to the other button, the said table receiving its movement from a shaft which at same time operates each of the tools, viz., the drills, the profiling and the finishing tool, which said tools receive rotary motion and also a vertical movement for the purpose of bringing them into operation and throwing them out of work at the proper moment to allow of the table being turned to present the next blanks to the ¹⁰⁰ tools.

2. In a machine of the kind specified, regulating the intermittent rotation of the table by means of a spring-detent which successively engages the teeth of a ring carried by the table, the pitch of said teeth being alternately short and long to correspond respectively to the long and short movements to be imparted to the table, the said detent being combined with the lever of another detent engaging in ¹¹⁰ notches of similar pitch to the teeth, the detents being so moved that when the last-mentioned detent is engaged the table is held stationary under the tools and the spring-detent is disengaged, and conversely, by the movement in the opposite direction, the table is released to permit of its angular movement and bring the spring-detent into engagement with the next following tooth.

3. In a machine of the kind herein specified, the receiving-tube disposed in alinement with the finishing and separating tool, at the opposite side of the table, having grippers at the

lower end for seizing the button as it is detached and in which the buttons successively detached rise and are finally delivered at the upper end of said tube as specified.

- 5 4. In a button-making machine, a table, means for alternately imparting rotary movements to the table at long and short distances, and drilling, shaping and finishing tools arranged over the table.
- 10 5. In a button-making machine, a table, means for imparting alternately long and short rotary movements to the table, a plurality of drills over the table, a shaping-tool, a finish-

ing-tool arranged below the table, a receiving-tube above the table in line with said finishing-tool, and blank-holding devices on the table.

The foregoing specification of my method of and machinery for the manufacture of buttons and other articles from vegetable ivory (corozo) and other materials signed by me this 14th day of October, 1902.

EMILE ROSENWALD.
